UNITED STATES PATENT OFFICE.

GUST V. MALMSTROM, OF KANE, PENNSYLVANIA.

COASTING-JUMPER.

1,181,025.

Specification of Letters Patent. Patented Apr. 25, 1916.

Application filed October 25, 1915. Serial No. 57,873.

To all whom it may concern:

Be it known that I, GUST V. MALMSTROM, a citizen of the United States, residing at Kane, in the county of McKean and State of Pennsylvania, have invented certain new and useful Improvements in Coasting-Jumpers; and I do declare the following to be a full, clear, and exact description of the invention, such as will enable others skilled in the art to which it appertains to make and use the same.

This invention relates to new and useful improvements in coasting sleds, and more particularly to a coasting sled of that type which employ a single runner, and have a seat supported above the same, and the primary object of the invention is to provide in a device of this character new and improved means for vertically adjusting the seat, so that the same may be adapted for use to children, of different sizes.

Another object of this invention is to provide in a device of this character, a coasting sled having a runner with a flexible adjustable front end, so that the same is adapted for use over lumpy and rough roads.

A further object of the invention is to provide a device of this character which is simple and durable in construction, inexpensive to manufacture, and one which will be very efficient in operation.

With these and numerous other objects in view, my invention consists of the novel features of construction, combination and arrangement of parts which will be herein referred to and more particularly pointed out in the specification and claims.

In the accompanying drawings: Figure 1 is a side elevation of the coasting sled; Fig. 2 is a front elevation; Fig. 3 is a section taken on the line 3—3 of Fig. 2; Fig. 4 is a section taken on the line 4—4 of Fig. 1; Fig. 5 is a horizontal section taken on the line 5—5 of Fig. 1; Figs. 6 and 7 are sections taken on the lines 6—6 and 7—7 of Fig. 1 respectively; and Fig. 8 is a central vertical longitudinal section of the front end of the runner.

In describing my invention, I shall refer to the drawings in which similar reference characters designate corresponding parts throughout the several views and in which the numeral 1 designates the lower portion of a hollow upright standard which is secured at its lower end as shown at 2 to a

wooden runner 3, which has its forward end 4 formed with a longitudinally extending slit 5 therein. This longitudinally extending slit 5 is for the purpose of giving an additional flexibility to the front end of the said runner for a purpose to be hereinafter more fully set forth. This wooden runner 3 has its lower surface covered with a steel runner or shoe 6, which has its opposite ends looped over the ends of the wooden runner 65 as shown at 7 and 8. The looped end 8 of the steel runner, which is the rear end of the same, has its extremity flat against the upper surface of the said wooden runner and is secured thereto by a bolt or rivet 9, which extends through the same and also through a countersunk hole in the lower surface of the steel runner. The looped forward end 7 of the steel runner is also secured to the wooden runner by a bolt or rivet 12 which projects 70 through the other extremity of the same, and the forward end of the wooden runner but does not extend through the adjacent portion of the steel runner.

The upright hollow standard 1 has disposed adjacent its upper end a clamp 11, which is either threadedly engaged therewith, or may be shrunk on the same, and this clamp or collar 11 has projecting outwardly from opposite sides of the same at diametrically opposite points, ears 12 and 13.

Connecting the ears 12 and the rear end of the runners, and connecting a portion of the ears 13 and the point adjacent the forward end of the wooden runner, are braces 80 14 and 15. These braces 14 and 15 comprise rods, which are securely fastened as clearly shown in Fig. 1, the lower end of the brace 14 being connected by the rivet 9 and the lower end of the brace 15 being connected to 85 the wooden runner by a bolt or rivet 16, which extends through the wooden runner 4 and also through the countersunk aperture in the steel runner 6. It will be obvious that the upper ends of these braces are secured to the ears 12 and 13 by pins extending transversely therethrough as is clearly shown in the drawings.

Secured to the upper portion of the ear 13, on the clamp or collar 11, is pivotally 105 connected a forwardly extending rod 17 which has its outer end screw threaded and is adapted to receive thereon one end of a turn buckle 18. The other end of this turn buckle 18 is connected with the thread- 110

ed end of the rod 19, which has its opposite free end loosely mounted in the looped forward end 7 of the steel runner 6. This loose connection, which is clearly shown at 5 20, comprises a transversely extending pin 21 projecting through an aperture in the flattened end of the rod 19, that projects through an elongated opening 22, in the upper portion of said forward end 7. By this 10 turn buckle connection between the upper end of the standard 1, and the flexible forward end of the runners, it will be obvious that upon moving the turn buckle 18 in one direction, the rods 17 and 19 will be drawn 15 closely together in alinement with one another, hence owing to the flexible forward end of the runners, the same will be elevated or lifted a certain determined distance, so that this sled is adapted for use 20 on rough or lumpy roads.

Telescopingly engaging the hollow standard 1, is an upper portion or section of the same which is designated by the numeral 23, and which comprises a rod adapted to fit 25 into the same, the said rod having mounted on its upper end a seat 24, as clearly shown at 25. This seat 24 has diverging downwardly and inwardly from the lower surface, at opposite sides, rods 26 which connect the same with a clamp 27 slidably mounted on the outer surface of the standard 1. This clamp 27 is provided with ears 28, which are adapted to engage the lower end of said rods, and said clamp is adapted 30 to be tightly engaged with the standard 1 at any desired point by means of the bolt 29, which is used to tighten the split portion of the same. If desired, any form of tightening means may be used on this clamp, it 35 only being essential that the same may be easily loosened and tightened so that it may be adjusted to various longitudinal positions on the standard 1. This adjustment allows the seat 24 to be moved longitudinally with respect to the standard 1, for the 40 purpose of which is obvious.

From the above description, it will be obvious that I have provided in this coasting sled, of the jumper type, a simple and efficient device, which has a vertically adjustable seat so that the same may be used for children of different sizes, and also a sled having a flexible forward end, adapted to be elevated to any predetermined height so 45 that the jumper may be used on rough and lumpy roads. This invention also embodies certain structural details, that make this sled very strong and durable, yet keep the

same very light so that it may be carried with very little effort.

From the foregoing description, the construction of my improved coasting sled or jumper, the manner of applying the same to use and the operation thereof, will be readily understood and it will be seen that I 65 have provided a simple, inexpensive and efficient means for carrying out the objects of the invention.

I claim:

1. A coasting sled comprising a runner 70 normally straight from end to end and adapted to have its front end flexed, a standard rising from the runner and supporting a seat, and an adjustable connection extending downwardly and forwardly from the 75 upper end of the standard to the front end of the runner, whereby said end of the runner may be flexed.

2. A coasting sled comprising a runner, a standard supporting a seat on its upper 80 end rising therefrom, a collar on said standard, a rod extending from the same, an additional rod loosely connected with the front end of said runner, and a turn buckle adjustably securing the free ends of the said 85 rods.

3. A coasting sled comprising a wooden runner having a flexible front end, a steel runner thereon having looped ends overlapping the opposite ends of said wooden runner, a standard supporting a seat on its upper end rising from the wooden runner, a collar on said standard, brace rods connecting said collar and runner, a rod projecting forwardly from said collar, a rod pivotally connected at one end with the forward looped end of the steel runner and the free ends of said rods adjustably connected by a turn buckle.

4. A coasting sled comprising a wooden 100 runner having its front end slit longitudinally between its upper and lower faces, a metal runner thereon having a looped front end overlapping said front end of the wooden runner and supporting a seat, and 105 a longitudinally adjustable connection between the standard and looped end of the metal runner whereby the front ends of the runners may be flexed.

In testimony whereof I have hereunto set 110 my hand in presence of two subscribing witnesses.

GUST V. MALMSTROM.
